UNITED STATES PATENT OFFICE.

DONALD McNICOL, OF NEW YORK, AND WILLIAM O. POWERS, JR., OF OSSINING, NEW YORK, ASSIGNORS OF ONE-HALF TO POSTAL TELEGRAPH-CABLE COMPANY, OF NEW YORK, N. Y., A CORPORATION OF NEW YORK.

RELAY FOR TELEGRAPH AND OTHER ELECTRIC CIRCUITS.

1,322,254.

Specification of Letters Patent.

Patented Nov. 18, 1919.

Application filed May 2, 1918. Serial No. 232,155.

To all whom it may concern:

Be it known that we, DONALD McNICOL and WILLIAM OLIVER POWERS, Jr., citizens of the United States, residing in the borough 5 of Manhattan, city, county, and State of New York, and in Ossining, county of Westchester, and State of New York, respectively, have invented certain new and useful Improvements in Relays for Telegraph and 10 Other Electric Circuits, of which the following is a specification.

The main object of the invention is to provide a relay adapted for use in circuits using either a direct current or an alternating 15 current.

Another object of the invention is to provide a relay with a yielding contact so disposed that it will be maintained in engagement with the opposite contact of the relay, 20 notwithstanding the vibrations or oscillations of the relay armature due to the cycles of the alternating current.

A further object of the invention is to provide a yielding contact adapted to be engaged by the contact on the relay armature, 25 said yielding contact being held in its normal or at rest position by balancing the opposed stress of two springs, whereby when the yielding contact is moved from its normal 30 position the stress of one spring will be relieved while the stress of the other spring will be increased. The purpose of this arrangement of springs is to bring the yielding contact back to a normal substantially 35 fixed position without employing a rigid stop.

There are other objects and advantages 40 of the invention, which will appear hereinafter.

In the drawing, Figure 1 is a plan view 45 of a relay made in accordance with this invention;

Fig. 2 a side elevation, one of the relay coils being omitted and the yielding contact support being shown in partial sectional view;

Fig. 3 a diagrammatic view of the relay 50 in an alternating current circuit; and

Fig. 4 a detail side elevation of a portion 55 of a relay, showing a modified form of yielding contact.

The relay shown in Figs. 1 and 2 is of the ordinary construction, except as herein specifically described, and is adapted to be

placed in a circuit in the ordinary manner. 55 The armature 1 is arranged to be held against its back stop 2, by means of the spring 3, the tension of said spring being varied by means of the adjusting screw 4. The back stop 2 may be adjusted to vary the 60 movement of the armature, as is common in this class of instruments. The armature 1 carries the back contact 6, which is adapted to engage the stop 2; and the forward contact 7, which is adapted to engage the yielding contact 8, this latter being mounted upon the rigid post 9, arranged between the coils 5. The contact 8 is secured to the upper end of a bar 10, pivoted at its lower end on a transverse pin 11, carried by the 70 post 9. Interposed between the bar 10 and the upper end of the post 9 is a compression spring 12, which tends to throw the pivoted bar 10 forwardly toward the armature and which is compressed when the pivoted bar is 75 moved rearwardly when the armature is attracted by an impulse of current through the coils. Connected to the upper end of the bar 10 above the spring 12 is a tension spring 13, the rear end of said spring being 80 connected to an adjusting screw 14. The spring 13 tends to pull the bar 10 rearwardly away from the armature and opposes the tension of the spring 12, so that the normal position of the bar 10 is determined by the balance of the forces exerted thereon by the two springs. The tension of the spring 13 may be varied by rotating the adjusting screw 14.

It is manifest that when the armature is 90 attracted by an impulse of current through the coils, its forward contact 7 will engage the contact 8 and force the pivoted bar 10 rearwardly, thereby compressing the spring 12 and placing it under tension and also relieving the tension of spring 13. If the impulse through the coils is of alternating current the armature will be vibrated slightly as it responds to the cycles or alternations of the current, but its contact 7 will be maintained in engagement with the contact 8 by the spring 12 and said contact will follow accurately the vibrations of the armature, thereby maintaining constantly the local circuit. The two opposed springs operating on 100 the yielding contact give the best results, for the reason that through the adjustment of the spring 13 the said contact may be 105

placed in a relatively fixed or predetermined normal position while at the same time the said contact is free to move or yield forwardly as well as rearwardly under the influence of the armature. The yielding contact will remain in engagement with the rear contact of the armature until there is a positive break in the current through the coils, which will permit the armature to 10 turn to its forward stop.

By reason of the pivotal mounting of the yielding bar 10 there will be a constant wiping action between the contacts 7 and 8, which will serve to keep said points clean 15 and bright.

As shown in Fig. 4, the armature 15 carries a spring contact 16, which is adapted to engage a fixed rear contact 17. In this form of the device the yielding contact 16 carried 20 by the armature will maintain its engagement with the fixed rear contact 17 during the vibrations of the armature, due to the alternations of current through the relay coils.

It is manifest from the foregoing that the principal object of the invention is to provide a relay with a yielding contact 25 adapted to respond readily to the vibrations of the armature caused by an impulse of alternating current through the relay coils. It is also manifest that the relay shown in the drawings and described herein, is adapted for use in all forms of circuits in which relays of the ordinary form may be used, and 30 that it is adapted for use in direct current and alternating current circuits without any change in the circuits through the relay 35 proper.

What we claim is:

1. A relay adapted to be operated by alternating or direct current, comprising an armature having a forward contact, relay 40

coils, a yieldable contact adapted to be engaged by the armature contact, a compression spring normally forcing said yieldable contact toward the armature, whereby said spring will be compressed when the contacts are engaged under the influence of a current impulse through the relay coils, and a retractile spring connected to said 50 yieldable contact and adapted to be placed under tension by the compression spring.

2. A relay adapted to be operated by alternating or direct current, comprising an armature having a forward contact, relay 55 coils, a pivoted upright bar carrying a contact adapted to be engaged by the armature contact, a compression spring normally forcing said bar toward the armature, whereby said spring will be compressed when the 60 contacts are engaged under the influence of a current impulse through the relay coils, and a retractile spring connected to said bar and adapted to be placed under tension by the compression spring.

3. A relay adapted to be operated by alternating or direct current, comprising an armature having a forward contact, relay 70 coils, a pivoted upright bar carrying a contact adapted to be engaged by the armature contact, a compression spring normally forcing said bar toward the armature, whereby said spring will be compressed when the contacts are engaged under the influence of a current impulse through the relay coils, a 75 retractile spring connected to said bar and adapted to be placed under tension by the compression spring, and means for adjusting the tension of the retractile spring.

In testimony whereof we hereunto affix 80 our signatures this 30th day of April, 1918.

DONALD McNICOL.
WILLIAM O. POWERS, Jr.
